GAME APPARATUS

Albin Frohne, Chicago, Ill., assignor to Rock-Ola
Manufacturing Corporation, Chicago, Ill., a
corporation of Illinois

Application March 20, 1935, Serial No. 11,917

13 Claims. (Cl. 273—121)

This invention relates to a game apparatus.

It is an object of this invention to provide an improved game apparatus which is relatively simple and inexpensive in construction and efficient in use.

Another object of the invention is to provide in a game apparatus, the combination of: a cabinet including a member providing a ball-playing surface having a ball exit opening or pocket there-in; means for propelling balls one at a time onto said playing surface so that they may enter into said ball exit opening; a ball projecting device mounted for vertical movement in said cabinet and normally disposed in ineffective position at 5 a level below said playing surface; and means including a device actuated by a ball entering said ball exit opening or pocket for elevating said ball-projecting device from its normal ineffective position at a level below the said playing surface 10 up to the level of the same.

A further object of the invention is to provide in the new game apparatus means including a device actuated by a played ball entering an exit opening or pocket in the playing surface for moving the ball-projecting device laterally over the ball-playing surface in a plane substantially parallel thereto so as to aim the ball-projecting device at any one of a row of ball exit openings or other targets provided in or upon the playing 15 surface.

An additional object of the invention is to provide in the new game apparatus means including a device actuated by a ball entering one of the exit openings or pockets on the playing surface 20 for actuating the ball-projecting device after the same has been swung laterally into position to project a ball at one of the ball exit openings or target in or upon the playing surface.

Still another object of the invention is to provide means including a device actuated by a spent or played ball for causing the gun turret unit or ball-projecting device embodied in the new apparatus to drop or disappear below the playing surface if the ball projected therefrom engages 25 one of the targets which are arranged in or upon the playing surface.

Other objects will appear hereinafter.

The invention consists in the novel combination and arrangement of parts to be hereinafter described and claimed.

The invention will best be understood by reference to the accompanying drawings, showing the preferred form of construction and in which:

Fig. 1 is a top plan view of a preferred form of 55 the new game apparatus;

Fig. 2 is a longitudinal vertical sectional view on line 2—2 in Fig. 1;

Fig. 3 is a vertical sectional detail view of the gun turret unit or ball-projecting device embodied in the apparatus, taken on line 3—3 in Fig. 2; 5 and showing the said gun turret in raised position;

Fig. 4 is a top plan view, on line 4—4 in Fig. 2, of a system of ball runways embodied in the new apparatus;

Fig. 5 is a top plan view, on line 5—5 in Fig. 2, of another system of ball runways embodied in the new apparatus;

Fig. 6 is an enlarged vertical sectional view, on line 6—6 in Fig. 3, of the ball-projecting device 10 or gun turret unit;

Fig. 7 is a sectional view on line 7—7 in Fig. 6;

Fig. 8 is a sectional view on line 8—8 in Fig. 6;

Fig. 9 is a sectional view on line 9—9 in Fig. 1;

Fig. 10 is a fragmentary perspective detail view 20 of the system of ball return runways shown in Fig. 5; and

Fig. 11 is a diagrammatic view of the wiring diagram or electromagnetic circuit embodied in the new game apparatus.

A preferred embodiment of the new game apparatus is shown in the drawings, is therein generally indicated at 15, and comprises a cabinet 16 which includes an inclined playing board or ball playing surface 17 having ball exit openings or 30 pockets 18 and 27 formed therein (Fig. 1).

The upper or playing surface of the inclined playing board 17 is divided, by a rail or wall 85, which extends transversely across the inclined playing board 17, relative to the long axis of the 35 same, into an upper ball playing area 25 and a lower ball playing area 26 (Fig. 1); the ball exit openings 27 being formed in the inclined playing board 17 within the lower playing area 26 thereof, and forming targets at which a ball may be 40 projected by means, and in a manner, presently to be described.

Leading onto the upper playing area 25 of the inclined playing board 17 is a ball runway or ramp 19 and arranged in the lower end portion 45 of this ramp or runway 19 is a ball-propelling device or plunger 20 by means of which balls may be propelled, one at a time, onto the upper playing area 25 of the inclined playing board 17 so that they may gravitate thereover and enter into the 50 ball exit openings 18.

Arranged below the inclined playing board 17 is an inclined floor 21 and arranged upon this inclined floor 21 is a system of ball return runways 22 which converge, at their lowers, into 55

a common runway 23 (Fig. 4), by means of which spent or played balls which pass through the exit openings 18 may be conducted back to a point adjacent the elevating device indicated at 5 83 (Fig. 1). Arranged in the radially outer end portion of each of the ball return runways 22, (as seen in Fig. 4) is a contact or circuit-closing device 24 and also arranged in each ball return runway 22 are one or more contacts or circuit-closing devices 71, while arranged in the common runway 23 is a contact or circuit-closing device 78 (Fig. 4).

Formed in the inclined playing board 17 is a cut-out opening 28 (Fig. 6) and movable into and 15 out of this opening 28 is a housing 29 which forms part of a disappearing gun turret unit or ball-projecting device, which is generally indicated at 10 30.

The disappearing gun turret unit or ball-projecting device 30 includes a gun barrel or muzzle 31 which is formed as a part of the housing 29 (Fig. 6) and arranged in the housing 29 behind the gun barrel 31 is a solenoid 32 which includes a movable element or ball-projecting member 20 33 (Fig. 6); this ball-projecting member 33 being normally urged into its initial or ineffective portion (as in Fig. 6) by means of a resetting spring 34 arranged thereon.

The housing 29, gun barrel 31, and ball-reprojecting member 32-33 of the gun turret unit or ball-projecting device 30 are mounted upon the upper end of a vertical elevator shaft or rod 35 which is slidably mounted in a supporting frame or guideway 36 which is arranged in the cabinet 35 16 below the inclined playing board 17 therein.

Mounted on the supporting frame or guide 36 is a solenoid 37 which includes a movable element 38 and pivotally connected to this member 38, as at 39, is an arm 40. This arm 40 is pivotally connected at its lower end, as at 41, to a member 42 which in turn, is pivotally mounted between its ends, as at 43, upon an arm 44 of the supporting frame 36. This member 42 is operatively connected, by means of a pin and slot connection 45 46-87 (Fig. 6) to the vertical elevator shaft or rod 35.

Mounted in the cabinet 16 below the inclined playing board 17, and at a point adjacent the solenoid 37, is a two-way circuit-closing switch 50 45 which includes two spaced and relatively stationary contacts 46 and a movable contact 47 arranged therebetween; this movable contact 47 being engageable by an extension or arm 48 of the member 42.

55 The ball exit openings 27 in the lower playing area 26 of the inclined playing board 17 constitute, in effect, targets at which a ball or missile 49 may be fired or projected from the barrel 31 of the ball projecting device or gun turret 30.

60 Arranged in the cabinet 16 between the inclined playing board 17 and the inclined floor 21, is an intermediate and inclined floor or casting 50 (Figs. 2, 5, and 9) in which is formed a plurality of radially arranged ball return runways 51, each of these runways 51 having communication with a corresponding one of the ball exit openings or targets 27. Formed in the casting 50 at the lower edge thereof is a transverse ball-bearing trough 52 and leading from the ball-receiving trough 52 65 into the barrel 31 of the gun turret or ball projecting device 30 is a ball runway 53 (Figs. 5 and 9). Likewise formed integrally with the casting 50 are two ball runways 54 (Figs. 5 and 9) and leading into these runways 54 are runways 56, each 70 of the runways 56 having communication at its

upper end with a ball exit opening 55, these ball exit openings 55 being formed in the inclined playing board 17 within the lower playing area 26 thereof and at the lower end of the latter.

Mounted upon the elevator shaft 35 is a collar or latch keeper 57 and engageable under this latch keeper 57 (Figs. 6 and 8) so as to hold the elevator shaft 35 and gun turret unit or ball-projecting device 29-30, etc., in a raised or elevated position is a latch arm 58, this latch member 58 10 being slidably mounted in a guide 59 which is attached to the supporting frame 36. This latch arm 58 is formed as a part of the movable element 60 of a solenoid 61 and is normally urged into latching engagement with the keeper 57 by 15 means of a spring 62 which is arranged on the member 60 (Fig. 6).

Mounted on the elevator shaft 35, below the latch keeper 57, is a member 63 which has a serrated upper edge portion 64 (Figs. 3, 6 and 7) 20 and engageable with this serrated edge portion 64 is a latch arm 65 which is carried by, and depends from, the slidable element 60 of the solenoid 61.

Likewise mounted upon the central elevator 25 shaft 35, at a point below the latch plate 63-64, is a movable magnetically attractable arm 66 which is adapted to be attracted selectively and successively by the cores 67 of a group of electromagnets 69 which are arranged upon a support- 30 ing plate 68, the supporting plate 68 being formed as a part of the supporting frame 36.

The housing 29 of the disappearing gun turret or ball-projecting device 30 has a skirt 70 and carried by the housing 29 at the bottom of the 35 latter is a laterally projecting pin 82 (Figs. 3 and 6 which is engageable) selectively with either of two corresponding cam edges 71 which are formed on a casting 72 which is suspended from the inclined playing board 17 below 40 the latter (Figs. 3 and 6) these cam edges 71 meeting in a vertical slot 73 which is formed in the member 72.

The new game apparatus includes a plurality of 45 associated electromagnetic circuits 74-79-80 and 84 which are shown, diagrammatically, in Fig. 11, and common to all of these circuits 74-79-80 and 84 is a suitable source of electric current, such as a battery of dry cells 75, which are arranged in the cabinet 16. 50

Arranged in each of the ball return runways 51 and 54 is a movable contact or circuit-closing member 76 (Fig. 5) and these contacts are adapted to close circuit selectively to the electromagnetic latch-releasing device 60-61, in a manner 55 presently to be described.

Operation

In playing the present game apparatus two sets of balls are used, that is, one set of balls 60 is used in conjunction with the playing area 25 and the ball exit openings or pockets 18 therein and another ball 49 which is independent of the balls used in conjunction with the playing area 25 and pockets 18, used in conjunction with the 65 playing area 26, pockets 27, and muzzle 31, this last-mentioned ball 49 being arranged upon the playing area 26 of the inclined board 17, and under the glass top of the cabinet, (Fig. 2) when the apparatus is assembled. 70

The disappearing gun turret unit or ball projecting device 30 is normally disposed in a lowered position (as in dotted lines, Fig. 6) with the bottom of the housing 29 resting upon the horizontal wall 78 of the supporting frame 36. 75

When a played ball, propelled up the ramp 19 onto the upper playing area 25 of the inclined playing board 17, enters into one of the ball exit openings 18, it drops into a corresponding one of the inclined ball return runways 22 and the contact 24 disposed therein, (Fig. 4), each of the contacts 24 being arranged directly below a corresponding one of the exit openings 18. This engagement of a played ball passing through an exit opening 18 with a corresponding contact 24 closes the elevator circuit 79 (Fig. 11) to the electromagnetic device or solenoid 31, thereby lowering the members 39 and 40 and pivoting the arm 42 (from dotted to full line position, Fig. 6). This movement of the member 42 raises the elevator shaft 35 and the gun turret unit or ball-projecting device 30 up into ball-projecting or effective position, as in full lines, Fig. 6.

Normally the two-way switch 45 is disposed in a position, as in dotted lines, Figs. 6 and 11, to close the elevator circuit 79. However, when this elevator circuit 79 is closed by the engagement of a played ball with one of the contacts 24, and the solenoid 31 is actuated, the movable element 47 of the two-way switch 45 is moved into full line position, Figs. 6 and 11, thereby opening the elevator circuit 79 so that any subsequently played ball entering a ball exit opening 18 and engaging a corresponding contact 24 will be ineffective in so far as the elevator circuit 79 and the elevating device 31-33-39-40-42-86-87-35-30 for the gun turret unit or projecting device 30 are concerned.

However, as the played ball passes over the contact 24, down the corresponding runway 22, it successively engages the contacts 77 in the corresponding runway 22, it being noted that there are two groups of the runways 22 and contacts 77 (Fig. 4), these groups of contacts 77 being designated "A" and "B", and are arranged at opposite sides of the center lines, as seen looking from bottom to top in Fig. 4, and from left to right in Fig. 7.

This successive engagement of a played ball, traveling down one of the runways 22, with the contacts 77 therein, successively closes the several circuits 84 (Fig. 11) to the electromagnets 69 which are arranged in the corresponding group "A" or "B" of the same, whereupon the magnetically attractable arm 66 is attracted, either in a clockwise or counterclockwise direction as seen in Fig. 7, depending upon in which group of contacts "A" or "B" the contacts 77 over which the actuating ball travels happen to be. This attraction of the magnetically attractable arm 66 by the electromagnets 69 moves the elevator shaft 35 and the gun turret unit or ball projecting device 30 carried thereby either in a clockwise direction, or in a counterclockwise direction, as the case may be, as seen in Fig. 1, thereby aiming the barrel 31 of the gun turret unit or ball projecting device 30 at a corresponding one of the ball exit openings or targets 27 in the lower playing area 26 of the inclined playing board 27.

After the played ball passes down one of the runways 22 and over the contacts 24 and 77 therein it enters into the common runway 23 (Fig. 4), and in so doing passes over the contact 78 therein (Fig. 4), thereby closing the circuit 83 to the electromagnet 32, whereupon the movable element or ball projector 33 of the solenoid 32 is moved (left to right, Fig. 6), thereby projecting the ball 49 out of the barrel 31 of the housing 29 onto the lower area 26 of the inclined

playing board 17 and in the direction of the ball exit opening or targets 27.

If the ball 49 thus projected out of the gun barrel 31 onto the lower area 26 of the inclined playing board 17 enters into or engages one of the ball exit openings or targets 27 it will drop through the latter into a corresponding one of the ball return runways 51, and will engage the contact or circuit-closing device 76 disposed in the corresponding runway 51, and thus close circuit 10 to the electromagnet 61, thereby retracting the latch arm 58-60 (from right to left, Fig. 6) out of latching engagement with the collar or latch keeper 57, whereupon the gun turret unit or projecting device 30 and its elevator shaft 35 will drop by gravity (into dotted line position, Fig. 6) into ineffective position below the inclined playing board 17, thereby simulating the movement of a disappearing gun turret.

If the barrel 31 of the projecting device 30 happens to be aimed at an angle relative to the longitudinal center line of the playing board 17 (as seen in Fig. 1), when the latching device 60-61 is released from latching engagement with the latch keeper or collar 57, and the elevator shaft 35 and ball-projecting device 30 commence to drop, the pin 82 carried by the housing 29 will ride over the corresponding cam edge 71 (Fig. 3) and will thereby pivot or rotate the projecting unit 30 about the vertical axis of its supporting shaft 35 into a position wherein the long axis of the barrel 31 is parallel to and coincident with the long axis of the playing board 17 as in Fig. 1.

If the ball 49 projected out of the barrel 31 fails to enter into one of the ball exit openings 27 it will gravitate over the lower playing area 26 of the inclined playing board 17 into one of the ball exit openings 55 and will pass through the latter into the corresponding runway 54 from which it will gravitate into the trough 50 and thence into the runway 53 (Fig. 5), whereupon it will engage the depending skirt 70 of the housing 29 and will be prevented thereby from entering into the housing 29, by way of the inlet 81 thereinto, and will thus be held against entering into the housing 29 and gun barrel 31 until the housing 29 is lowered to register the inlet opening 81 therewith to the runway 53, whereupon the ball stopped in the runway 53 will travel through the inlet 81 into the barrel 31 of the ball-projecting device 30; it being noted that as the thus played ball 49 travels through one of the runways 54 it closes the corresponding switch 76 therein, and thus actuates the solenoid 60-61, (Fig. 11), thereby withdrawing the latch arm 58 out of latching engagement with the collar 57, whereupon the shaft 35 and the projecting unit 30 carried thereby will drop by gravity, thus registering the inlet with the runway 53, whereupon the ball 49 will travel through the inlet 81 into the muzzle 31.

As the elevator shaft 35 and the ball-projecting unit 30 carried thereby drop by gravity, the member 42 is pivoted from full to dotted line position (Fig. 6), whereupon the arm 48 of the member 42 pivots the two-way switch 45 into dotted line position (Fig. 6), thereby arranging the elevator circuit 79 in a position to be closed by the engagement of a played ball with one of the contacts 77 (Fig. 11).

As the ball projecting device 30 is pivoted about the vertical axis of the shaft 35 by engagement of a played ball with the contacts 77 and the consequent closing of the circuits 84 to the elec-

romagnets 69, the arm 65 rides over the serrated edge 64 of the member 63 and this engagement of the arm 65 with the serrated edge 64 of member 63 prevents the ball-projecting device 30 from moving about its vertical axis during the operation of the ball-projecting member 32-33.

While I have illustrated and described the preferred form of construction for carrying my invention into effect, this is capable of variation and modification, without departing from the spirit of the invention. I, therefore, do not wish to be limited to the precise details of construction set forth but desire to avail myself of such variations and modifications as come within the scope of the appended claims.

1. In a game apparatus, the combination of: a cabinet including a member providing a ball-playing surface having a ball receiving pocket therein; means for propelling balls one at a time onto said playing surface so that they may enter into said ball receiving pocket; a ball projecting device mounted for vertical movement in said cabinet and normally disposed in ineffective position at a level below said playing surface; and means including a device actuated by a ball entering said ball receiving pocket for elevating said ball-projecting device from its normal ineffective position at a level below the said playing surface up to the level of the same.

2. In a game apparatus, the combination of: a cabinet including a member providing a ball-playing surface having a ball receiving pocket therein; a ball projecting device mounted for vertical movement in said cabinet and normally disposed at a preselected level relative to said playing surface; and means including a device actuated by a ball entering said ball receiving pocket for moving said ball-projecting device from one level to another in said cabinet relative to said playing surface.

3. In a game apparatus, the combination of: a cabinet including a member providing a ball-playing surface having a ball receiving pocket therein, means for propelling balls one at a time onto said playing surface so that they may enter into said ball receiving pocket; a ball projecting device mounted for vertical movement in said cabinet and normally disposed at a level below said playing surface; means including a device actuated by a ball entering said ball receiving pocket for elevating said ball-projecting device from its normal position at a level below the said playing surface up to the level of the same; and means including a device likewise actuated by a ball entering said ball receiving pocket for actuating said ball-projecting device so as to project a ball therefrom over said playing surface.

4. In a game apparatus, the combination of: a cabinet including a member providing a ball-playing surface having a ball receiving pocket therein; a ball projecting device mounted for vertical movement in said cabinet and normally disposed at a preselected level relative to said playing surface; means including a device actuated by a ball entering said ball receiving pocket for moving said ball-projecting device from one level to another relative to said playing surface; and means including a device likewise actuated by a ball entering said ball receiving pocket for actuating said ball-projecting device so as to project a ball therefrom over said playing surface.

5. In a game apparatus, the combination of: a cabinet including a member providing a ball-playing surface having a ball receiving pocket there-

in; means for propelling balls one at a time onto said playing surface so that they may enter into said ball receiving pocket; a ball projecting device mounted for both vertical and horizontal movement in said cabinet and normally disposed at a level below said playing surface; means including a device actuated by a ball entering said ball receiving pocket for elevating said ball-projecting device from its normal position at a level below the said playing surface up to the level of the same; and means including a device likewise actuated by a ball entering said ball receiving pocket for pivoting said ball-projecting device about its vertical axis over said playing surface after the said ball-projecting device has been elevated up to the level of said playing surface.

6. In a game apparatus, the combination of: a cabinet including a member providing a ball-playing surface having a ball receiving pocket therein; a ball projecting device mounted for both vertical and horizontal movement in said cabinet and normally disposed at a preselected level relative to said playing surface; means including a device actuated by a ball entering said ball receiving pocket for moving said ball-projecting device from one level to another in said cabinet relative to the said playing surface; and means including a device likewise actuated by a ball entering said ball receiving pocket for pivoting said ball-projecting device about its vertical axis after the said ball-projecting device has been moved from one level to another relative to said playing surface.

7. In a game apparatus, the combination of: a cabinet including a member providing a ball-playing surface having a ball receiving pocket therein; means for propelling balls one at a time onto said playing surface so that they may enter into said ball receiving pocket; a ball projecting device movably mounted in said cabinet and normally disposed at a level below said playing surface; means including an electromagnetic device actuated by a ball entering said ball receiving pocket for elevating said ball-projecting device from its normal position at a level below the said playing surface up to the level of the same; and means likewise including an electromagnetic device actuated by a ball entering said ball receiving pocket for actuating said ball-projecting device so as to project a ball therefrom over said playing surface.

8. In a game apparatus, the combination of: a cabinet including a member providing a ball-playing surface having a ball receiving pocket therein; a ball projecting device mounted for both vertical and horizontal movement in said cabinet and normally disposed at a level below said playing surface; means including an electromagnetic device actuated by a ball entering said ball receiving pocket for elevating said ball-projecting device from its normal position at a level below the said playing surface up to the level of the same; and means likewise including an electromagnetic device actuated by a ball entering said ball receiving pocket for swinging said ball-projecting device over said playing surface in a plane substantially parallel to the latter after the said ball-projecting device has been elevated up to the level of said playing surface.

9. In a game apparatus, the combination of: a cabinet including a member providing a ball-playing surface having a ball receiving pocket therein; means for propelling balls one at a time onto said playing surface so that they may enter into said ball receiving pocket; a ball projecting device movably mounted in said cabinet for both vertical and horizontal movement and normally

disposed at a level below said playing surface; means including an electromagnetic device actuated by a ball entering said ball receiving pocket for elevating said ball-projecting device from its 5 normal position at a level below the said playing surface up to the level of the same; means likewise including an electromagnetic device actuated by a ball entering said ball receiving pocket for swinging said ball-projecting device over said 10 playing surface in a plane substantially parallel to the latter after the said ball-projecting device has been elevated up to the level of said playing surface; and means also including an electromagnetic device actuated by a ball entering said ball 15 receiving pocket for actuating said ball-projecting device, after the same has been swung over said playing surface, so as to project a ball therefrom over said playing surface.

10. In a game apparatus, the combination of: a 20 cabinet including a member providing a ball-playing surface having a ball receiving pocket therein; means for propelling balls one at a time onto said playing surface so that they may enter into said ball receiving pocket; a ball projecting device movably mounted in said cabinet and normally disposed at a level below said playing surface; means including an electromagnetic device actuated by a ball entering said ball receiving pocket for elevating said ball-projecting device 25 30 from its normal position at a level below the said playing surface up to the level of the same; a target upon said playing surface; means likewise including an electromagnetic device actuated by a ball entering said ball receiving pocket for actuating said ball-projecting device, after the same has been elevated up to the level of said playing surface, so as to aim the same at said target; and means likewise including an electromagnetic device actuated by a ball entering said ball receiving pocket for actuating said ball-projecting device so as to project a ball therefrom at said target. 35

11. In a game apparatus, the combination of: a cabinet including a member providing a ball-playing surface having a ball receiving pocket therein; means for propelling balls one at a time onto said playing surface so that they may enter into said ball receiving pocket; a ball projecting device movably mounted in said cabinet for both vertical and horizontal movement and normally disposed at a level below said playing surface; means including an electromagnetic device actuated by a ball entering said ball receiving pocket for elevating said ball-projecting device from its normal position at a level below the said playing surface up to the level of the same; a target upon said playing surface; means including an electromagnetic device actuated by a ball entering said ball receiving pocket for swinging said ball-projecting device over said playing surface in a plane substantially parallel to the latter, after the said ball-projecting device has been elevated up to the level of said playing surface, so as to aim the same at said target; and means including an electromagnetic device actuated by a ball entering said ball receiving pocket for actuating said ball-projecting device, after the latter has been elevated up to the level of said playing surface, so as to project a ball therefrom at said target; means for latching said ball-projecting device in raised position; and means including a device actuated by a ball engaging said target for releasing said latching means from latching engagement with said ball-projecting device so as to enable the latter to drop by gravity back into its normal position below said playing surface. 45

12. In a game apparatus, the combination of: a cabinet including a member providing a ball-playing surface having a ball receiving pocket therein; means for propelling balls one at a time onto said playing surface so that they may enter into said ball receiving pocket; a ball projecting device movably mounted in said cabinet for both vertical and horizontal movement and normally disposed at a level below said playing surface; means including an electromagnetic device actuated by a ball entering said ball receiving pocket for elevating said ball-projecting device from its normal position at a level below the said playing surface up to the level of the same; a target upon said playing surface; means including an electromagnetic device actuated by a ball entering said ball receiving pocket for swinging said ball-projecting device over said playing surface in a plane substantially parallel to the latter, after the said ball-projecting device has been elevated up to the level of said playing surface, so as to aim the same at said target; and means including an electromagnetic device actuated by a ball entering said ball receiving pocket for actuating said ball-projecting device so as to project a ball therefrom at said target. 50

13. In a game apparatus, the combination of: a cabinet including a member providing a ball-playing surface having a ball receiving pocket therein; means for propelling balls one at a time onto said playing surface so that they may enter into said ball receiving pocket; a ball projecting device movably mounted in said cabinet for both vertical and horizontal movement and normally disposed at a level below said playing surface; means including a device actuated by a ball entering said ball receiving pocket for elevating said ball-projecting device from its normal position at a level below the said playing surface up to the level of the same; a target upon said playing surface; means including a device actuated by a ball entering said ball receiving pocket for swinging said ball-projecting device over said playing surface in a plane substantially parallel to the latter, after the said ball-projecting device has been elevated up to the level of said playing surface, so as to aim the same at said target; and means including a device actuated by a ball entering said ball receiving pocket for actuating said ball-projecting device, after the latter has been elevated up to the level of said playing surface, so as to project a ball therefrom at said target; means for latching said ball-projecting device in raised position; and means including a device actuated by a ball engaging said target for releasing said latching means from latching engagement with said ball-projecting device so as to enable the latter to drop by gravity back into its normal position below said playing surface. 55

ALBIN FROHNE.
